UNITED STATES PATENT OFFICE.

STEPHEN P. BURDICK, OF OAKLAND, CALIFORNIA.

VEHICLE.

SPECIFICATION forming part of Letters Patent No. 417,143, dated December 10, 1889.

Application filed April 13, 1889. Serial No. 307,105. (No model.)

To all whom it may concern:

Be it known that I, STEPHEN POWELL BURDICK, a citizen of the United States, and a resident of Oakland, in the county of Alameda 5 and State of California, have invented certain new and useful Improvements in Vehicle-Springs; and I do declare the following to be a full, clear, and exact description of the invention, such as will enable others skilled in the art to which it appertains to make and use the same, reference being had to the accompanying drawings, and to letters or figures of reference marked thereon, which form a part of this specification.

15 Figure 1 of the drawings is a representation of this invention and is a bottom view. Fig. 2 is a detail. Fig. 3 is a vertical section taken through a portion of a cart, with one spring.

20 This invention has relation to vehicle-springs; and it consists in the construction and novel combination of parts, as herein-after set forth.

In the accompanying drawings, the letter Z 25 designates the bottom of the body of a vehicle, to which are secured the lateral transverse spiral springs A, each spring being axially extended at its ends to form journals a, which are seated in bearings E, secured to 30 the bottom of the vehicle, or preferably to cleats thereof, as indicated.

The inner journal of each spring is extended to form the reversely-bent attachment-arm C, which is provided with a flattened end c, nearly at right angles to said arm C, and perforated for the securing-bolts c', whereby the arm is fastened to the body of the vehicle. This reversely-bent arm C extends along the entire length of the spring- 35 body portion back to the edge of the body, where it is secured thereto.

The outer journal of each spring is extended and bent, at b, to form the oblique lever-arm B, the end of which is pivoted to a hanger F, secured to the gear-bar or side bar M. The lever-arm is pivoted directly to the head f of the hanger, and said head is turned obliquely inward, so that its inclination will correspond with that of said lever-arm.

40 In order to provide room for the upper portions of the spiral springs, the cleats O of the body are secured as indicated at o'.

The bearings E are provided with bearing-blocks e, which are secured in position upon the journal of the springs by the bent upper 55 ends h of the bolts H, said bent upper ends engaging the grooved holders e'.

The lever-arm B extends obliquely downward, outward, and forward, as shown, and as the reversely-bent attachment-arm C is also 60 bent around forward of the coil portion of the spring it is apparent that the weight of the load tends to close the spring. The spring consists of the lever-arm, the spiral body, and the attachment-arm, and it has not only the 65 spiral action, but the torsional effect of the reversed attachment-arm. It will also be apparent that the working points or points of pressure on the body are at its outer edge or sill as the bent end of the attachment-arm is 70 in line with said edge, as is also the outer bearing of the spring. In this combination it will be observed that it is designed to extend the lever-arms of the forward and of the rear springs forward and obliquely down- 75 ward, so that they will have uniform parallel motion; and when these springs are applied to carts it is apparent that the load at each downward movement thereof is shifted a little backward, so that the horse is in a meas- 80 ure relieved during the downward movements.

The parallel arrangement of the springs renders it an easy matter to add or remove a pair of springs, according to the weight of the 85 load. When the wagon is designed to carry loads of various weights, it is provided with extra bearings and hangers and with extra springs, which can be quickly removed when a light load is to be carried, and when the 90 load is heavy readily replaced.

Between the inner bearings E of the lateral springs is usually located a bearing-block P.

Having described this invention, what I claim, and desire to secure by Letters Patent, 95 is—

1. The vehicle -spring consisting of the transverse spiral body portion, the outer journal-extension of said body portion bent downward and forward and outward, forming 100 an oblique lever-arm, the inner journal-extension, and the reversely-bent attachment-arm extending therefrom along the entire length of the spiral body portion, and also forward

in the same general direction as the said lever-arm, and having the flattened bent end provided with fastening-perforations, substantially as specified.

- 5 2. The combination, with the vehicle-body having the bearings E and the side gear-bars, of the front and rear spiral springs laterally arranged in pairs, as shown, and having the reversely-bent attachment-arms secured to
- 10 the outer edges of the body, and the oblique lever-arms passing through bearings at the outer edges of the body and extending down-

ward, outward, and forward to each other and pivoted directly to the oblique heads of the hangers of the gear-bars, said reversely-bent attachment-arms and lever-arms extending forward in the same general direction, substantially as specified. 15

In testimony whereof I affix my signature in presence of two witnesses.

STEPHEN P. BURDICK.
